US00D732754S

(12) **United States Design Patent**
Roberson et al.

(10) **Patent No.:** **US D732,754 S**
(45) **Date of Patent:** **** Jun. 23, 2015**

(54) **CUTLERY BASKET COVER**

(71) Applicant: **BSH Home Appliances Corporation**,
Irvine, CA (US)

(72) Inventors: **Lindsay Roberson**, Durham, NC (US);
Jeff Vogus, New Bern, NC (US)

(73) Assignee: **BSH Home Appliances Corporation**,
Irvine, CA (US)

(**) Term: **14 Years**

(21) Appl. No.: **29/472,062**

(22) Filed: **Nov. 8, 2013**

Related U.S. Application Data

(62) Division of application No. 29/446,584, filed on Feb. 26, 2013, now Pat. No. Des. 701,358, which is a division of application No. 29/391,796, filed on May 13, 2011, now Pat. No. Des. 681,288.

(57) **CLAIM**

The ornamental design for a cutlery basket cover, as shown and described.

DESCRIPTION

FIG. 1 is a front perspective view of a cutlery basket cover; FIG. 2 is a rear view thereof;

FIG. 3 is a front view thereof;

FIG. 4 is a top view thereof;

FIG. 5 is a bottom view thereof;

FIG. 6 is a right side rear view thereof with the left side view being a mirror image thereof; and,

FIG. 7 is a bottom perspective view thereof.

The broken lines of the cutlery basket show surrounding structure or environment and do not form part of the claimed design.

1 Claim, 3 Drawing Sheets
